UNITED STATES PATENT OFFICE.

GEORGE M. HUBBARD, OF NEW HAVEN, CONNECTICUT, ASSIGNOR TO W. & E. T. FITCH, OF SAME PLACE.

DESIGN FOR A CLASP FOR BELTS.

SPECIFICATION forming part of Design No. 21,065, dated September 22, 1891.

Application filed August 31, 1891. Serial No. 404,347. Term of patent 7 years.

To all whom it may concern:

Be it known that I, GEORGE M. HUBBARD, of New Haven, in the county of New Haven and State of Connecticut, have invented a new Design for a Clasp for Belts, (Case D;) and I do hereby declare the following, when taken in connection with accompanying drawing and the letters of reference marked thereon, to be a full, clear, and exact description of the same, and which said drawing constitutes part of this specification and represents a face view of the eye portion of the clasp.

This invention relates to a design for clasps for securing a belt around the body, with special reference to the eye portion of the clasp; and it consists in the configuration of the eye portion of the clasp, as shown in the accompanying illustration.

A represents the loop by which the eye is secured to the band. Parallel with the loop is the representation of a straight bar *a*, this bar being represented as connected to one side of the loop by transverse bars *f f*, as shown in the accompanying illustration.

I claim—

The design for a clasp for belts, as described, and shown in the accompanying illustration.

In testimony whereof I have signed this specification in the presence of two subscribing witnesses.

GEORGE M. HUBBARD.
